GARDNER COX, OF PIERREPONT, NEW YORK.

Letters Patent No. 92,017, dated June 29, 1869.

IMPROVEMENT IN WATER-WHEELS.

The Schedule referred to in these Letters Patent and making part of the same.

To all whom it may concern:

Be it known that I, GARDNER COX, of Pierrepont, in the county of St. Lawrence, and State of New York, have invented a new and valuable Improvement in Water-Wheels; and I do hereby declare that the following is a full, clear, and exact description of the construction and operation of the same, reference being had to the annexed drawings, making a part of this specification, and to the letters of reference marked thereon.

My invention has relation to water-wheels; and

It consists mainly in the construction and arrangement, in a novel manner, of devices by which the gates of a turbine wheel may be easily and expeditiously opened or closed at will.

The letter A, of the drawings, represents the bottom plate; letter B, the upper plate; and letters C, the gates, of my turbine water-wheel.

These gates are pivoted, as shown, to the plates respectively, the upper ends of the pivots working and resting in the curved slots e of the upper plate, as represented.

The letter E is a representation of the shaft of the wheel; and letters F, of the chutes or aprons that conduct the water to the gates.

The letter P represents a plate or bar, affixed to

the upper surface of plate B, as shown, and having a ratchet-head thereto, to operate with the pinion H, next mentioned.

The letter H represents a pinion, affixed to an upright post, that rotates in suitable journals or pivot-blocks, contiguous to plate B.

The office of this ratchet-headed plate, post, and pinion, is to conjointly serve as the means by which the plate B may be moved to the right or left, and thereby the gates be opened or closed, as may be desirable.

To open the gates, the pinion H is turned to the left. To close the gates, I turn said pinion to the right.

Claim.

What I claim as my invention, and desire to secure by Letters Patent, is—

The plates A, B, and G, gates C, chutes F, and pinion H, when constructed and arranged to operate substantially as and for the purposes specified.

GARDNER COX.
